UNITED STATES PATENT OFFICE.

ARTHUR B. SPERRY, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,337,671.

Specification of Letters Patent. Patented Apr. 20, 1920.

Application filed June 6, 1918. Serial No. 238,484.

To all whom it may concern:

Be it known that I, ARTHUR B. SPERRY, a citizen of the United States, residing at New York, in the county of New York and

5 State of New York, have invented certain new and useful Improvements in Telephone-Exchange Systems, of which the following is a full, clear, concise, and exact description.

10 This invention relates to telephone exchange systems and particularly to an improved system for controlling the severing of telephonic connections.

An object of the invention is to provide 15 an improved circuit arrangement under the control of both parties to an established connection whereby either may cause the complete release of the switching means involved in the connection.

20 Heretofore means whereby either party to an established connection may cause the release of the switches involved independently of the other has been provided but the present invention contemplates a more efficient 25 arrangement employing a simpler and improved circuit and a novel conception of means for performing this function.

In accordance with the main feature of the invention, a connecting circuit is provided 30 through which a call may be extended to an automatic exchange so arranged that, upon the establishment of a connection, a bridge is closed across the incoming and another bridge across the outgoing end of the 35 connecting circuit. Each bridge controls a contact in the circuit of the other, and each is controlled by the subscriber or operator at his end of the circuit so that either subscriber or operator may control the opening 40 of both bridges, whereupon the switches are restored to normal.

In the embodiment of the invention disclosed in the drawing, the calling line is an operator's cord circuit by means of which a 45 subscriber's line is manually extended to a distant automatic telephone exchange. However, it will be obvious to those skilled in the art that the invention is equally well applicable to systems in which an operator's 50 intervention is not necessary to establish a connection.

Only so much is disclosed in the drawing as is necessary for a clear understanding of the invention. The apparatus and circuits 55 employed in the automatic telephone ex-

change are the same as in the system disclosed in Patent No. 1,175,119 to A. H. Blessing, with slight modifications in the connector circuit.

The operation of the system shown in the 60 drawing is as follows:

A calling subscriber at station 1, desiring to obtain connection with a called station 2, associated with a distant automatic exchange, causes the operation of well-known 65 means to extend his line to a manual operator's cord circuit 3. The manual operator, having communicated with the calling subscriber, inserts plug P into jack J. A trunk line 4, 5 terminating in jack J, leads to an 70 operator's position located at the distant automatic exchange. The manual operator depresses her ringing key RK, and connects an alternating current generator 6 and ground through the tip and ring contacts of 75 plug P and jack J, trunk conductors 4 and 5, a condenser 7, and the left-hand winding of a relay D. The relay D becomes energized and closes a locking circuit for itself from ground, through the armature and 80 back contact of a relay C, the armature, front contact, and the right-hand winding of relay D to grounded battery. A branch of this circuit extends through a lamp L to 85 grounded battery. The lamp L is lighted and the automatic exchange operator is thus informed that a call is awaiting attention at her position. She depresses her listening key and causes the telephonic connection of her head-set (not shown) with the manual 90 operator's head-set. Having learned the number of the desired line, the automatic exchange operator actuates her key K, whereupon a calling device CD of the well-known type is connected to the outgoing end 95 of her trunk 4, 5. By means of the calling device, the operator causes the setting of the first and second selectors and the connector, in accordance with the numerical designation of the called line. When the connector 100 switch is seized, the line relay LR becomes energized and causes in turn the energization of relay 11 which establishes a holding circuit for relay 10 of the second selector. By attracting its armature, relay 10 closes 105 a holding circuit for relay 8 of the first selector which relay is previously energized in a well known manner.

In response to the actuation of the key K, a circuit is closed from ground, through con- 110

tact k' of key K and the right-hand winding of a relay A to grounded battery. The relay A becomes energized. When a relay 8 is energized as above described, it connects 5 ground through the conductor 9, the contacts of a release key R, and the winding of a relay B to grounded battery, causing the energization of relay B. Relays A and B, being now energized, a bridge is closed 10 across the incoming end of the trunk conductors 4 and 5, which bridge extends from ground, through a relay 12, the tip contacts of plug P and jack J, conductor 4, the inner front contact, armature and left-hand winding of relay A, right-hand armature and front contact of relay B, the left-hand winding of the relay D, conductor 5, the ring contacts of jack J and plug P and the winding of relay 13 to grounded battery. Relays 15 20 12, 13, A and D are locked up by current flowing through this circuit. Another bridge, closed by relays A and B across the outgoing end of the trunks, extends from conductor 4, through the normal contact of key K, the winding of the relay C, the left-hand front contact and armature of relay B, the outer front contact and armature of relay A, and the normal contact of key K to the conductor 5. This bridge is supplied 25 30 with battery through the line relay LR of the connector, and the left-hand armature and back contact of a slow-acting relay 20.

When the called party answers the call by removing his receiver from the switchhook, 35 the relay BB becomes energized, and causes in turn the energization of a relay 21. The relay 21 closes an energizing circuit for the relay 20, and the latter locks up through its right-hand armature and front contact, and 40 the right-hand armature and front contact of slow-acting relay 11. Upon the energization of the relay 21 and subsequent energization of relay 20, the second bridge extends through the left-hand armature and front 45 contact of relay 21. When the relay C becomes energized, it extinguishes lamp L and causes the lighting of lamp L' which indicates that trunk 4, 5 is energized.

When the connection is established, the relay A is under the control of both the distant 50 manual exchange operator and the called line through the agency of relay B, and the relay C is under the control of the called line (through the agency of relay B), and the distant manual exchange operator 55 (through the agency of the relay A).

When the called subscriber restores his receiver to the switchhook, the relay BB becomes deenergized and opens the circuits 60 including relays 21, LR and C. The deener-

gization of relay LR results in the successive deenergization of relays 11, 20, 10, 8, and B. Under the control of relays 8, 10 and 11 the selectors and the connector are restored to normal. Upon the deenergization of relay 65 C the lamp L' is extinguished. The relay B causes the opening of the bridge across the incoming end of the trunk line, whereupon relays A, D, 12 and 13 become deenergized. The relays 12 and 13 control well-known 70 supervisory signals (not shown) at the manual operator's position.

The clearing of the trunk under the control of the manual exchange operator, should she receive a clearing-out signal from 75 the calling subscriber before the called subscriber has replaced his receiver, is accomplished by removing the plug P from the jack J. The locking circuit of the relays A and D being thereby opened, these relays become deenergized and the relay A opens the bridge across the outgoing end of the trunk. The relay C and the line relay LR of the connector become deenergized, whereupon the switches and the trunk circuit 4, 5 are 80 restored to normal in the above described manner.

What is claimed is:

1. In a telephone exchange system, a calling and a called line, an operator's position, 90 a trunk, means including automatic switching devices for establishing a connection between said lines over said trunk, bridges across the incoming and outgoing ends of said trunk established when said connection 95 is made, a relay at said operator's position for controlling a supervisory signal thereat, said relay being responsive to the closing of said bridges, means under the control of either the calling or the called line for opening its bridge and therethrough open the other bridge, and means for releasing said switching devices when said bridges are opened.

2. In a telephone exchange system, a calling and a called line, a trunk, means including automatic switching devices for establishing a connection between said lines over said trunk, bridges across the incoming and outgoing ends of said trunk established 105 when said connection is made, a relay through contacts of which said bridges extend, said relay being under the control of either line for opening one of said bridges and therethrough open the other bridge, and 110 means for releasing said automatic switching devices when said bridges are opened.

In witness whereof I hereunto subscribe my name this 1st day of June, A. D. 1918.

ARTHUR B. SPERRY.
